LOCK

Edward N. Jacobi, Milwaukee, Wis., assignor to
 Briggs & Stratton Corporation, Milwaukee,
 Wis., a corporation of Delaware

Application June 11, 1934, Serial No. 730,076

21 Claims. (Cl. 70—46)

This invention relates to new and useful improvements in locks and refers more particularly to cylinder locks.

It is an object of this invention to provide a cylinder lock having greater security against unauthorized opening and one in which decoding by conventional methods is rendered impossible.

With the above and other objects in view which will appear as the description proceeds, the invention resides in the novel construction, combination and arrangement of parts substantially as hereinafter described and more particularly defined by the appended claims, it being understood that such changes in the precise embodiment of the hereindisclosed invention may be made as come within the scope of the claims.

In the accompanying drawings, I have illustrated one complete example of the physical embodiment of my invention constructed according to the best mode so far devised for the practical application of the principles thereof, and in which:

Figure 1 is a perspective view of the lock cylinder and casing, shown disassembled;

Figure 2 is a cross section view through the assembled lock, taken on the plane of the line 2—2, of Figure 3;

Figure 3 is a view partly in side elevation and partly in longitudinal section, taken on the plane of the line 3—3 of Figure 2;

Figure 4 is a cross section view taken through Figure 3 on the plane of the line 4—4;

Figure 5 is a detail perspective view looking into the casing;

Figure 6 is a detail section view taken through Figure 4 on the plane of the line 6—6;

Figure 7 is a detail section view through the cylinder taken on the plane of the line 7—7 of Figure 1; and

Figure 8 is a fragmentary detail section view through Figure 7 on the plane of the line 8—8.

Referring now more particularly to the accompanying drawings, in which like numerals indicate like parts throughout the several views, the numeral 5 designates generally the casing of the lock, bored as at 6 to receive a cylinder 7. The cylinder 7 has an enlarged flange or head 8 at its outer end to cover the front of the casing 5 with an annular projection 9 on the underside of the head engaging in a counterbore 10.

A keyway 11 extends longitudinally into the cylinder from its front end, as is customary, to communicate with a transverse tumbler receiving chamber 12. A plurality of locking tumblers 13 mounted in the chamber 12 are spring urged

to project their ends 14 into a longitudinal tumbler receiving groove 15 in the casing to normally secure the lock cylinder in a locked position. The tumblers are retractable within the circumference of the cylinder to free the cylinder for rotation by the insertion of a proper key 16.

One side of the longitudinal tumbler receiving groove 15 has an inclined wall 17 leading from the bottom of the groove to a step 18, which forms a space for a longitudinally pivoted locking bar 19, which functions in a manner similar to the locking member shown and described in Patent No. 1,950,723, issued to J. W. FitzGerald, March 13, 1934.

As best shown in Figure 2, this pivoted locking bar, which extends along the entire depth of the bore 6, has the cross sectional shape of a pawl, and the nose thereof is normally disposed in the path of the projected tumbler ends to be engaged thereby upon rotation of the cylinder, effected before all of its tumblers have been properly retracted. Upon such rotation of the cylinder, while any one tumbler remains in its projected position, the pivoted locking member 19 is swung to its operative position by the engagement of such tumbler therewith.

To prevent accidental turning of the locking member 19 to its operative position, it is frictionally held against turning by a spring 19' at the inner end of the recess in which it is mounted, and which is placed in compression by the engagement of a pin 20 on the front end of the locking member with the under-surface 21 of the cylinder head 8.

It is noted that this under-surface of the head 8 is cut back to define an annular channel 22, the inner wall of which is defined by a continuation of the cylindrical surface of the cylinder. The purpose of this annular channel will be brought out hereinafter.

Inasmuch as the locking member 19 might automatically remain inoperative for long periods of time during which the lock would be operated only by its proper key, there is a strong possibility that it might become frozen either through corrosion, or deposits of foreign matter. To offset this possibility, means are provided to exercise the locking member 19, or in other words, move the same upon each operation of the lock. This means consists merely in the provision of a recess 21' in the under-surface 21 of the head 8, into which the end of the pin 20, moves during each rotation of the lock cylinder to and from locked position, the pin 20 dropping into the recess 55

as it passes by virtue of its being yieldably projected forwardly by the spring 19'.

To accommodate the projection of the tumbler ends 23 beyond the periphery of the cylinder during the insertion and removal of the key, a second longitudinal tumbler receiving groove 24 is formed in the casing diametrically opposite the groove 15. One side of this groove 24 is formed jointly by two pivoted levers 25 and 26. These levers are pivotally mounted at their inner ends by a pin 27 passing through overlapping inner end portions of the levers and ears 28 formed in the casing by a longitudinal slot 29 cut entirely through its wall for the reception of the levers 15 and transverse recesses or pockets 30 adjacent the inner end of the slot 29.

As hereinbefore noted, the levers 25 and 26 are overlapped, that is, they are in side by side relationship, and as best shown in Figure 3, the lever 25, which may be termed the forward lever, is cut out as at 31 to receive a projecting portion 32 on the lever 26. The face of the projecting portion 32 of the lever 26 is thus flush with the face of the lever 25. Together, these two faces or side walls of the levers 25 and 26 define one side of the tumbler receiving groove 24, so that if the cylinder is turned to its position illustrated in Figure 2, which position is defined by the locking member 19 engaging the projected end of any tumbler, the opposite ends 23 of the tumblers will be directly beneath the levers 25 and 26.

Both levers 25 and 26 are acted upon by torsion springs 33 and 34 respectively, so that the forward ends of the levers are at all times biased toward the center of the lock. The torsion springs are coiled about the projected ends of the pivot pin 27, and have one end anchored to the casing and their other ends engaging in holes formed in the sides of the levers 25 and 26.

When the lock is assembled, that is, with the cylinder inserted in the casing, the inward movement of the front ends of the levers is limited by the engagement thereof with the cylindrical surface of the cylinder, so that the inner surfaces of the levers form continuations of the wall of the bore. In this assembled relationship, the extreme forward ends of the levers, which are cut down as at 35, extend into the annular channel 22 in the head of the cylinder (see Figure 3). There is sufficient clearance, however, between the outer wall of the channel 22 and the outer faces of the levers to permit a limited outward swinging movement on the part of the levers against the action of their respective springs.

It is noted that the relative widths of the tumbler ends 14 and 23 with respect to the effective widths of their respective grooves 15 and 24 are such that when the cylinder is in its locked position and the tumbler ends 14 engage the solid side of groove 15, the diagonally opposite corners of the tumblers are spaced a comfortable distance from the solid side of the groove 24, so that unless the cylinder can be released for counterclockwise rotation, engagement of the tumbler ends 23 with the solid edge of the groove 24 is impossible.

A degree of clockwise rotation is, however, permitted the cylinder, while the tumblers are active, the limit of which is defined by the engagement of the locking member 19 with the tumbler ends 14. Inasmuch as the levers define that side of the groove 24 toward which the adjacent ends of the tumblers are moved during such permitted rotation of the cylinder as in an attempt to pick the lock or to decode the same, it follows

that the inner surfaces of the levers form the only abutment against which the tumblers can be brought to bear in an attempt to decode the lock, but in view of the fact that the levers are yieldable, decoding cannot be effected.

The effectiveness of the levers is further enhanced by utilizing one of the levers as a surface against which the front three tumblers bear and the other lever for the remaining inner two tumblers.

Another feature of protection afforded by this construction is obtained through the provision of a notch 36 in the outer wall of the annular channel 22, into which the extreme forward end 35 of either of the two levers may engage in the event the levers are pushed outwardly and the cylinder forcibly turned. The engagement of the lever ends in the notch 36 thus defines a positive limit for such forced rotation.

It is also observed that the inner side faces of the levers are longitudinally grooved as at 37 and that the adjacent ends of the tumblers are notched as at 38. Consequently, if an attempt is made to pick the lock, such attempt will generally be frustrated by the engagement of the notches 38 onto the ledges formed by the grooves 37 in the levers.

A still further protection against possible decoding is afforded by stepping part of the diameter of the bore 6, as at 39. In this manner the only surfaces against which the tumblers might be brought to bear are disposed at different distances from the axis of the cylinder and inasmuch as it is necessary to have a surface continuous and unbroken and also parallel with the axis of the cylinder throughout its entire extent to enable decoding of the lock by bringing the tumblers to bear against such surface, it follows that by stepping part of the bores the requisite axially straight surface is not present and decoding is rendered impossible.

The security of the lock is further increased by the provision of a slidably mounted locking pin 40 carried by the cylinder and arranged to engage in the forward extremity of the groove 15. The proper key 16 has a notch 41 to align with the inner end of this locking pin and permit the same to be cammed into the cylinder as the cylinder is turned. In entering the notch 41, the pin 40 positively holds the key against retraction until the cylinder is again turned back to its fully locked position and precludes leaving the cylinder in an apparently locked but actually unlocked position, with the tumblers resting on the locking member 19, which is then in its inoperative position. Also, unless the key used is equipped with such notch 41, it follows that the pin 40, being secured against inward movement, will prevent rotation of the cylinder.

From the foregoing description taken in connection with the accompanying drawings, it will be readily apparent to those skilled in the art, that this invention affords novel means for preventing decoding of a cylinder lock and that it also provides novel means for adding to the security of the lock by preventing forced rotation of its cylinder and precluding picking of the lock by conventional methods.

What I claim as my invention is:

1. In a lock, a bored casing, a lock cylinder in the casing bore, locking tumblers mounted in the cylinder to project radially therefrom into a groove in the casing, and a yieldable member defining one side of the groove and the adjacent wall of the bore, said member yielding radially as

tumblers are projected endwise thereagainst in an attempt to decode the lock.

2. In a lock, a bored casing, a lock cylinder in the casing bore, locking tumblers projectable radially from the cylinder, means to lock the cylinder against rotation beyond a predetermined limited degree in the event of rotation imparted thereto while any locking tumbler is in any but fully retracted position, and yieldable means carried by the casing and disposed opposite the tumbler ends when the cylinder is in said predetermined position of rotation, said means yielding radially as tumblers are projected endwise thereagainst in an attempt to decode the lock.

15 3. In a lock, a bored casing having a tumbler receiving groove in communication with its bore, a lock cylinder in the casing bore, tumblers projectable radially from the cylinder into said groove, and a movable member carried by the casing and defining one edge of said tumbler groove, said member moving radially as tumblers are projected endwise thereagainst, whereby decoding of the lock by bringing the tumblers against said edge of the groove is precluded.

25 4. In a lock, a bored casing, a cylinder rotatable in the casing bore, radially projectable tumblers carried by the cylinder and engageable with the casing to secure the cylinder positively against turning in one direction from a predetermined position but allowing a predetermined degree of rotation in the other direction without requiring retraction of the tumblers, and a yieldable member carried by the casing with one surface thereof flush with the bore in the casing, said member being so positioned as to be opposite the ends of the tumblers when the cylinder is turned its permitted distance in said second direction, and said member yielding as tumblers are brought to bear thereagainst in an attempt to decode the lock.

30 5. In a lock, a bored casing having diametrically opposite tumbler receiving grooves communicating with its bore, a lock cylinder rotatable in the casing bore, tumblers carried by the lock cylinder and projectable radially into the tumbler receiving grooves, the relative sizes of the projected tumbler ends and the grooves being such as to allow a predetermined degree of rotation on the part of the cylinder without requiring retraction of the tumblers, and a yieldable member carried by the casing and defining one wall of the opposite tumbler groove, said yieldable member being so located as to be opposite the adjacent ends of the tumblers when the cylinder is turned its predetermined permitted degree and yielding as tumblers are brought to bear thereagainst in an attempt to decode the lock.

35 6. In a lock, a bored casing having a longitudinal tumbler receiving groove communicating with its bore, a lock cylinder in the casing bore, tumblers carried by the cylinder and projectable radially therefrom into said groove, and a pivoted lever defining one side of the groove, the pivot for said lever lying in a plane transverse to the lock axis and being spaced radially from the lock axis so that said lever swings in a plane substantially radial to the lock axis.

40 7. In a lock, a bored casing having a longitudinal tumbler receiving groove communicating with its bore, a lock cylinder in the casing bore, tumblers carried by the cylinder and projectable therefrom into said groove, a pivoted lever defining one side of the groove, means to yieldably hold the lever in a position with one surface

thereof forming substantially a continuation of the bore of the casing, and the pivotal axis for said lever being transverse to the lock axis and so located that said lever yields radially with respect to the lock axis as tumblers are projected endwise against said surface of the lever in an attempt to decode the lock.

45 8. In a lock, a bored casing, a lock cylinder rotatable in the casing bore, tumblers projectable from the cylinder for engagement with the casing to secure the cylinder in a locked position, springs to yieldably urge the tumblers in one direction, and a radially yieldable member defining the only wall surface against which the tumblers may be brought to bear by lifting them endwise against the action of their springs in an attempt to decode the lock.

50 9. In a lock, a bored casing, a lock cylinder rotatable in the casing bore, tumblers projectable radially from the cylinder into operative engagement with the casing to positively secure the cylinder against rotation in one direction but permitting limited rotation in another direction, spring means to so project the tumblers, and radially yieldable means affording the only surface against which the tumblers may be brought to bear by lifting them endwise against the action of their springs in an attempt to decode the lock.

55 10. In a lock, a bored casing, a lock cylinder rotatable in the casing bore, tumblers projectable radially from the cylinder into operative engagement with the casing to positively secure the cylinder against rotation in one direction but permitting limited rotation in another direction, spring means to so project the tumblers, and a member carried by the casing with one surface thereof forming substantially a continuation of its bore, said surface being the only surface against which the tumblers may be brought to bear by lifting them endwise against the action of their springs in an attempt to decode the lock and said member yielding radially as the tumblers are lifted endwise against its said surface.

60 11. In a lock, a bored casing having diametrically opposite tumbler receiving grooves communicating with its bore, a lock cylinder rotatable in the bore, tumblers carried by the lock cylinder and projectable radially therefrom, spring means to project the tumblers into one of the tumbler receiving grooves, the engagement of the projected tumbler ends with the grooves positively securing the cylinder against rotation in one direction but permitting a limited rotation in the other direction, a yieldable member carried by the casing and defining one wall of the other tumbler receiving groove, the other wall of said tumbler receiving groove being sufficiently far from the adjacent edges of the tumblers when the cylinder is in its locked position to preclude engagement of the said edges of the tumblers with the edge of said side wall of the groove as in an attempt to decode the lock, and the yieldable member overlying the tumblers when the cylinder is turned its permitted distance, whereby in an attempt to decode the lock said member yields as the tumblers are brought to bear thereagainst.

65 12. In a lock, a bored casing, a lock cylinder rotatable therein, locking tumblers carried by the cylinder and engageable with the casing to secure the cylinder in locked position, and a portion of the bore wall being radially yieldable so that as tumblers are projected endwise there-

- against, said portions move outwardly to prevent decoding of the lock.
13. In a lock, a bored casing, a lock cylinder in the casing bore, tumblers carried by the cylinder and projectable radially therefrom, and a radially yieldable member carried by the casing and having a surface normally forming a continuation of the casing bore, said member yielding radially as tumblers are projected endwise thereagainst in an attempt to decode the lock.
14. In a lock, a bored casing, a lock cylinder in the casing bore, tumblers carried by the cylinder and projectable radially therefrom, and a plurality of members movably mounted on the casing and having surfaces adapted to form continuations of the bore in the casing, and said members yielding radially as tumblers are projected endwise thereagainst in an attempt to decode the lock.
15. In a lock, a bored casing, a lock cylinder mounted in the casing bore, tumblers carried by the cylinder and projectable radially therefrom for engagement with the casing to secure the cylinder in locked position, and a member extending longitudinally of the casing and movably mounted in the wall of the casing and normally in a position at which its inner surface forms substantially a continuation of the casing bore, means to yieldably maintain said member in said position, and said member yielding radially as tumblers are projected endwise thereagainst in an attempt to decode the lock.
16. In a lock, a bored casing, a lock cylinder mounted in the casing bore, locking tumblers projectable radially from the cylinder for engagement with the casing to secure the cylinder in locked position, and a lever pivotally mounted at one end portion of the casing, and disposed longitudinally in a slot in the casing with its inner surface normally forming substantially a continuation of the bore of the casing, yieldable means to maintain the lever in its normal position, and said lever yielding radially as tumblers are projected endwise against its inner surface in an attempt to decode the lock.
17. In a lock, a bored casing having a longitudinal tumbler receiving groove communicating with its bore, a lock cylinder in the bore tumblers carried by the cylinder and projectable radially therefrom into said groove, and a movable member carried by the casing to define one side of said groove, said movable member and the tumblers having notched portions adapted to inter-engage to preclude picking of the lock.
18. In a lock, a bored casing having a tumbler receiving groove communicating with its bore, a lock cylinder rotatable in the casing bore, locking tumblers projectable radially from the cylinder for engagement in the groove, and a pivoted lever carried by the casing and defining one side of said groove and a portion of the bore of the casing so that said pivoted lever affords an edge against which the tumblers may be brought to bear, said lever and the tumblers having cooperating notched portions to inter-engage and preclude picking of the lock.
19. In a lock, a casing having a bore part of which is stepped with different diameters, said casing also having a tumbler receiving groove one side of which communicates with the stepped portion of the bore, and locking tumblers projectable radially from the cylinder and into said groove, the stepped formation of the bore adjacent said side of the groove precluding decoding of the lock by bringing the tumblers to bear against the edge of the groove at said side thereof.
20. In a lock, a bored casing, a lock cylinder rotatable in the bore, locking tumblers projectable radially from the cylinder, a movable member carried by the casing and having a part normally forming a continuation of the bore in the casing, said part affording the only surface against which the tumblers may be brought to bear in an attempt to decode the lock, and said members yielding outwardly in the event tumblers are brought to bear thereagainst, and means to effect an interlocking connection between said member and the cylinder in the event said member is moved outwardly by the engagement of tumblers therewith to positively secure the cylinder against rotation.
21. In a lock having a casing and a lock cylinder rotatable therein, tumblers carried by the cylinder and engageable with the casing to releasably secure the cylinder against rotation, a movable locking member carried by the casing and lying in a position engageable by any tumbler not fully retracted to be moved thereby to a position positively interlocking the casing and cylinder in the event of rotation of the cylinder while such tumbler remains in a projected position, and means to move said locking member with a non-locking movement during each actuation of the lock by a proper key which retracts all of the tumblers to preclude mechanically freezing the locking member in its inoperative position.

EDWARD N. JACOBI. 55
